Primary Examiner — Michael A. Pratt*(74) Attorney, Agent, or Firm* — Birch, Stewart, Kolasch & Birch, LLP(57) **CLAIM**

The ornamental design for a stand for display device, as shown and described.

DESCRIPTION

1. Stand for display device

1.1 : Perspective

1.2 : Front

1.3 : Back

1.4 : Left

1.5 : Top

1.6 : Bottom

1.7 : Reference view

The broken lines depict portions of the stand for display device that form no part of the claimed design; reproduction 1.1 is a perspective view of the stand for display device; reproduction 1.2 is a front view thereof; reproduction 1.3 is a back view thereof; reproduction 1.4 is a left view thereof where the right view is a mirror image; reproduction 1.5 is a top view thereof; reproduction 1.6 is a bottom view thereof; reproduction 1.7 is a reference view thereof showing an example of the usage of the subject design in which the subject article is folded and then a display device is placed on the stand.
